A CORPORATION OF MASSACHUSETTS.

DEVICE TO PREVENT REPEATED INDICATION OF WEFT EXHAUSTION

Application filed July 16, 1928. Serial No. 293,220.

This invention relates to improvements in weft replenishing mechanism of the type operating with a regularly moving transerrer having a weft detecting element mounted thereon and it is the general object of the invention to provide means for preventing a repeated indication of weft exhaustion on transferring picks by means of an element which is moved and held in position to prevent the repeated indication.

In weft replenishing mechanisms of the type shown in patent to Ryon 1,372,316 there is employed a regularly moving transerrer arm having a weft detector moved into engagement with the yarn by movement of the transerrer arm each detecting beat of the loom. In later modifications of the original Ryon construction there is employed an indicating plunger which remains in indicating position after being moved to such position or released to be moved to said position by the weft detector.

Whether the indicating plunger be of the type shown in the original Ryon patent or the later type it occasionally happens that on the beat of the loom when a bobbin is being transferred into the depleted shuttle the detector will operate to indicate so as to repeat the indication. A device to prevent such repeated indication is shown in co-pending application Ser. No. 293,014, filed by King and it is an important object of our present invention to provide a mechanism operating to accomplish substantially the same result achieved by the King construction but wherein the device which prevents the repeated indication may remain in preventing position an appreciable length of time to give more certainty to the operation thereof.

It is a more particular object of our present invention to provide a friction device which will be moved from inactive to preventing position by mechanism controlled by the incoming bobbin and in further providing means such as friction to hold the device in preventing position until the transerrer arm has moved upwardly to a position where the released indicating plunger cannot act to initiate replenishment.

With these and other objects in view which

will appear as the description proceeds, our invention resides in the combination and arrangement of parts hereinafter described and set forth in the claims.

In the accompanying drawings, wherein a convenient embodiment of our invention is set forth,

Fig. 1 is a side elevation of a portion of a multicolor weft replenishing mechanism having our invention applied thereto and showing the preventing device in normal position to permit the first indication to initiate replenishment.

Fig. 2 is a view similar to Fig. 1 but with the preventing device moved to operative position where it is effective to prevent a repeated indication.

Fig. 3 is a horizontal section taken on line 3—3 of Fig. 2, and

Fig. 4 is a vertical section taken on line 4—4 of Fig. 2.

Referring to the drawings, we have indicated a loom frame 10 and a weft replenishing mechanism 11 supported thereby. The mechanism as set forth herein is more specifically of the type shown in patent to Ryon No. 1,030,748 modified by the type of motion shown in Ryon Patent No. 1,372,316. A transerrer arm 12 is pivoted on the fixed stud 13 and is oscillated in a vertical plane by a rod 14, said rod moving the transerrer arm downwardly on detecting beats of the loom when the lay is in its extreme forward position and moving the transerrer arm upwardly on non-detecting beats of the loom.

An indicating lever 15 is pivoted on a stud 16 fixed to the frame 11 and has at the lower end thereof an upwardly and forwardly inclined cam face 17 which cooperates at the time of indication with a plunger 18 slidably mounted on the transerrer arm 12.

By reference to the previously identified patents the manner of controlling the plunger 18 will be understood and it is sufficient for the purposes of our present invention to state that under normal conditions said plunger is in the full line position shown at the lower part of Fig. 3, or in non-indicating or inner position, and that at the time of indication of weft exhaustion the detector 19, the lower

end of which is shown in Fig. 1, will act so as to result in movement of the plunger 18 to the dotted line position shown at A in Fig. 3. When in this position the plunger will act 5 on the cam face 17 to rock the indicating lever 15 in a clockwise direction as viewed in Fig. 1 when the transerrer arm is raised.

The indicating lever is provided with a horizontally extending arm 20 which is operatively connected by means of an upwardly 10 extending link 21 to a color slide indicated generally at C and slideable back and forth in fixed bearings 22. Said color slide is also angularly movable in the bearings and is 15 moved by mechanism not shown but acting in time with the shuttle boxes of the loom to have operative relation with one or another of the vertical slides 23.

In the operation of the structure thus far 20 described the transerrer arm will move up and down for a complete cycle of movement every alternate pick of the loom, and when sufficient weft is present the plunger 18 will be in non-indicating position, so that on the 25 first part of the upward movement of the transerrer arm the indicating lever will remain at rest or in the full line position shown in Fig. 1. On the next or non-indicating beat of the loom a lug 24 on the transerrer arm 30 will engage an extension 25 on the horizontal lever 20 to rock the indicating lever in a counter-clockwise direction as viewed in Fig. 1 to the position shown in dotted lines in said figure. This last described movement of the 35 indicating lever 15 takes place on every non-detecting beat of the loom and acts to rock color slide C.

When the weft in the active shuttle is substantially exhausted, however, the plunger 40 18 will move to the dotted line position A shown in Fig. 3 and upon upward movement 45 of the transerrer arm the indicating lever will move in the righthand direction to cause rocking of the color slide in a direction opposite to that which takes place on non-detecting beats of the loom. For a further 50 description of the controlling devices between the indicating lever 15 and the weft replenishing mechanism reference may be had to the previously mentioned patent to Ryon 1,372,316.

In carrying our present invention into effect we provide means to prevent movement 55 of the plunger 18 into operative indicating relationship with the indicating lever 15 at the time a fresh bobbin is being inserted into the shuttle S. Were this not accomplished it would be possible for said indicating plunger to cause a repeated actuation of the indicating 60 lever so as to call for a second transfer which would be unnecessary and if repeated a sufficient number of times would exhaust the supply of reserve bobbins.

Accordingly, in carrying our invention into 65 effect we provide a fixed stud 50 secured to

the frame 11 preferably at a point located to the rear of the indicating lever 15. The stud 50 is secured in a hub 51 which may be cast integral with the frame 11 and there is mounted on said hub a compression spring 52 which lies between the hub 53 of a preventer member 54 and a washer 55 positioned on the stud by a cotter pin 56. The compression spring 52 forces the hub 53 against the hub 51 and tends to hold the preventer member 54 in whatever position it may occupy relatively to the stud and frame.

The forward end of the preventer member 54 is provided with a wing 57 which, as shown in Fig. 4, has the outer or right hand vertical face 58 thereof somewhat to the right of the corresponding face 59 which is formed on the indicator lever 15 and lies adjacent the frame 11. The wing 57, as shown in Fig. 1, is normally in low position where it does not interfere with the longitudinal movement of the indicating plunger 18.

The rear support for the butt of the bobbin is indicated at 60 and is secured to a stud 61 by means of a set screw 62. Said stud 61 extends through and is rotatable in the frame 11 and through a hub 63 formed as part of the frame and has adjustably secured thereto an operating finger 64 held in adjusted longitudinal and angular position relatively to the stud by a set screw 64'. Said operating finger extends rearwardly and is held against a fixed stop 65 by means of a torsion spring 66 one end of which passes under the stop 65 and the other end of which is wrapped around the hub 63 and then extends over the operating finger 64. The spring 66 therefore acts to hold the rear bobbin butt support 60 yieldingly in bobbin retaining position.

A coupling member 70 is provided with 105 slot 71 through which extends a securing screw 72 extending into the preventer member 54. The upper end of the coupling extends horizontally as at 73 over the finger 64. The coupling may be adjusted both angularly and transversely with respect to the preventer member, but is normally held fixed to the latter so as to cause movement thereof when lifted by the finger 64.

In the operation of our improvements, when a bobbin B is moved downwardly from the magazine into the shuttle S by the transerrer arm the support 60 will rock about its axis in a clockwise direction as viewed in Fig. 1, causing the operating finger 64 to move away from the stop 65 to the position shown in dotted lines in Fig. 2. This movement on the part of the operating finger raises the coupling 70 and therefore lifts the preventer member from the position shown in Fig. 1 to that shown in Fig. 2.

By referring to Fig. 2 it will be seen that the wing 57 is aligned with the plunger 18 and therefore should the detector 19 give a false indication said plunger will not be able 130

to establish indicating operative relationship with the indicating lever 15. Therefore, as the transerrer arm 12 moves upwardly, the indicating plunger will remain at rest, and 5 as the transerrer continues to ascend the plunger will engage the cam face 80 formed on the indicating lever and shown more particularly in Fig. 4. Said cam 80 serves to reset the indicating plunger in the manner 10 set forth in patent to Ryon No. 1,369,473.

As the transerrer arm continues its upward movement the indicating lever will be moved as previously described to the dotted line position shown in Fig. 1, and as it does 15 so the cam face 17 will engage the upwardly and forwardly extending face 81 of the wing 57 and move the latter downwardly to restore the preventer member to the normal position indicated in Fig. 1.

20 The preventer member is required to be in elevated position for a very short time and for this reason the spring 52 can be light and inasmuch as practically all of the weight of the preventer member is on one side of the 25 supporting stud 50, said member will tend to move to its lowest position due to vibration of the loom. Should it be desired to vary the extent of movement of the wing 57 the screw 72 may be loosened and the coupling 70 given 30 the proper setting along the operating finger 64.

From the foregoing it will be seen that we have provided means for holding a preventer member into the path of the indicating 35 plunger in mechanisms of the type referred to, the effect of the preventer member being to restrain movement of the indicating plunger and hold the same against establishing indicating operative relationship with 40 the indicating lever to prevent a repetition of indications. It will further be seen that the device for accomplishing this result, which is shown herein as depending upon friction to retain its various setting, is controlled by 45 the outgoing bobbin. It will also be noted that the transerrer arm acting as is normal in motions of this type swings the indicator lever to reset the preventer member to normal position. Furthermore, the coupling 70 50 is of such a nature that the extent of movement of the wing 57 may be varied. It will also be noted that the face 58 of the wing 57 is nearer the plunger 18 than is the face 59 of the indicator lever 15, the effect of this 55 relationship being that as the transerrer arm is elevated there will be no tendency for the plunger 18 when urged to move toward indicating position to engage and rock the 60 indicator lever.

Having thus described our invention it will be seen that changes and modifications may be made therein by those skilled in the art without departing from the spirit and 65 scope of the invention and we do not wish to

be limited to the details herein disclosed, but what we claim is:

1. In a weft replenishing mechanism, a regularly moving transerrer arm having transferring and non-transferring strokes, 70 means to initiate replenishment at exhaustion of weft, an element movable at the time of transfer by a force derived from the transerrer arm to a position to prevent initiation of weft replenishment, and means to hold 75 said element in preventing position when the transerrer arm is moving on its non-transferring stroke.

2. In a weft replenishing mechanism, a regularly moving transerrer arm, means to 80 initiate replenishment at exhaustion of weft, an element movable at the time of transfer by a force derived from the transerrer arm to a position to prevent initiation of weft replenishment, and means to hold said element 85 in preventing position after transfer.

3. In a weft replenishing mechanism, a regularly moving transerrer arm having transferring and non-transferring strokes, 90 an indicating lever, means carried by the transerrer arm to give the lever an indicating movement at substantial weft exhaustion to initiate weft replenishment, an element movable into restraining position relatively to the means to prevent the means from engaging 95 the indicating lever on a transferring beat of the loom, mechanism to move said element into restraining position at the time of transfer, and a device to hold said means in restraining position while the transerrer arm has a non-transferring stroke. 100

4. In a weft replenishing mechanism, a regularly moving transerrer arm, an indicating lever, means carried by the transerrer arm to give the lever an indicating 105 movement at substantial weft exhaustion to initiate weft replenishment, an element movable into restraining position relatively to the means to prevent the means from engaging the indicating lever on a transferring beat of the loom, mechanism to move said element into restraining position at the time of transfer, and a device to hold said means in restraining position after transfer. 110

5. In a weft replenishing mechanism having a bobbin to be transferred, a movable support for the bobbin when the latter is in transfer position, means to transfer the bobbin, means to initiate weft replenishment at substantial exhaustion of weft, an element movable by the support at the time of transfer 120 into restraining position relatively to the means to prevent initiation of weft replenishment at the time of transfer, and means to hold said element in restraining position 125 after transfer.

6. In a weft replenishing mechanism, a transerrer arm having a regular movement, an indicating member mounted on the transerrer arm and movable into indicating po- 130

- sition at the time of weft exhaustion, an indicating lever to cooperate with the member to initiate weft replenishment, and means independent of the lever and movable by a force derived from the transferrer arm at the time of transfer into restraining position relatively to the member to prevent the latter from moving into indicating relationship relatively to the indicating lever.
7. In a weft replenishing mechanism, a transferrer arm having a regular movement, an indicating member mounted on the transferrer arm and movable into indicating position at the time of weft exhaustion, an indicating lever to cooperate with the member to initiate weft replenishment, means independent of the lever and movable by a force derived from the transferrer arm at the time of transfer into restraining position relatively to the member to prevent the latter from moving into indicating relationship relatively to the indicating lever, and friction means acting on the restraining means to hold the same in restraining position relatively to the member after transfer.
8. In a weft replenishing loom, a regularly moving transferrer arm, an indicating member movable to initiate replenishment of weft, an element carried by the transferrer arm and movable at weft exhaustion into indicating relationship with the member to cause the latter to initiate weft replenishment, and means independent of the indicating member and movable by a force derived from the transferrer arm into restraining position relatively to the element to prevent the latter from establishing indicating relationship with the member on transferring beats of the loom.
9. In a weft replenishing loom, a regularly moving transferrer arm, an indicating lever movable to initiate weft replenishment, a plunger movable with the transferrer arm and into indicating relationship with the indicating lever at exhaustion of weft, an arm mounted on the loom independently of the indicating lever, and means acting at the time of transfer to move said arm into position to prevent the plunger from establishing indicating relationship with the indicator lever and thereby prevent initiation of weft replenishment on transferring picks of the loom.
10. In a weft replenishing loom, a regularly moving transferrer arm having transferring and non-transferring strokes, an indicating plunger movable with the transferrer arm, an indicator lever to have indicating relationship with the plunger at the time of weft exhaustion to initiate weft replenishment by motion derived from the transferrer arm, a pivoted element mounted independently of the indicating lever and movable by a force derived from a transferrer arm into position to prevent indicat-

ing relationship between the plunger and the lever, and means establishing a connection between the indicator lever and the element during the non-transferring stroke of the transferrer arm to move said element out of restraining position relatively to the plunger.

11. In a weft replenishing loom, a regularly movable transferrer arm having a transferring and a non-transferring stroke, means to initiate weft replenishment at substantial weft exhaustion including a member carried by the transferrer arm, a restraining element for the member movable into restraining position relatively to said member to prevent initiation of weft change during the transferring stroke of the transferrer arm, and means operative by the transferrer arm during the non-transferring stroke of said arm to move the element out of restraining position relatively to the member.

12. In a weft replenishing loom, a regularly moving transferrer arm, a plunger slidably mounted thereon and carried thereby, an indicating lever to have indicating relationship with said plunger at substantial exhaustion of weft to cause indicating movement of the lever by the transferrer arm to initiate weft replenishment, an arm pivotally mounted on the loom independently of the indicating lever, a support for a bobbin in transfer position, connections between the support and the arm to move the latter into restraining position with respect to the plunger on transferring beats of the loom to prevent said plunger from establishing indicating relationship with the indicator lever, friction means to hold said element in restraining position, and means operative by the transferrer arm to move said element out of restraining position with respect to the plunger.

13. In a weft replenishing loom, a regularly moving transferrer arm, a plunger slidably mounted thereon and carried thereby, an indicating lever to have indicating relationship with said plunger at substantial exhaustion of weft to cause indicating movement of the lever by the transferrer arm to initiate weft replenishment, an arm pivotally mounted on the loom independently of the indicating lever, a support for a bobbin in transfer position, connections between the support and the arm to move the latter into restraining position with respect to the plunger on transferring beats of the loom to prevent said plunger from establishing indicating relationship with the indicator lever, friction means to hold said element in restraining position, and means operative by the transferrer arm to move said element out of restraining position with respect to the plunger, the pivot of said arm being eccentric with respect to the pivot of the indicating lever.

14. In a weft replenishing loom, a regu-

larly moving transerrer arm having transferring and non-transferring strokes, an element carried by the transerrer arm and movable at weft exhaustion to indicating position, means to prevent said element from moving to indicating position on transferring beats of the loom, and mechanism operative by a non-transferring stroke of a transerrer arm to reset said means.

10 In testimony whereof we have hereunto affixed our signatures.
